1

Latin name of the genus and species of the plant claimed:
Fragaria x ananassa.

Variety denomination: 'BG-12.3266'.

BACKGROUND OF THE INVENTION

The present invention relates to a new and distinct strawberry variety named 'BG-12.3266'. This new variety is a result of a controlled cross made in 2012 in an ongoing breeding program between strawberry variety designated 'BG-3.324' (U.S. Plant Pat. No. 23,256) as the seed (female) parent, and strawberry variety designated 'Florida Radiance' (U.S. Plant Pat. No. 20,363) as the pollen (male) parent. The variety is botanically known as *Fragaria x ananassa*.

The seedling resulting from the aforementioned cross was selected from a controlled breeding plot in Ventura County, Calif. in the winter of 2014. After its selection, the new variety was asexually propagated by stolons in both Siskiyou County, Calif. and San Joaquin County, Calif. The new variety was extensively tested over the next several years in fruiting fields in Ventura County, Calif. This propagation has demonstrated that the combination of traits disclosed herein as characterizing the new variety are fixed and remain true-to-type through successive generations of 25 asexual reproduction.

(57) **ABSTRACT**

This invention relates to a new and distinct variety of strawberry plant named 'BG-12.3266'. This new strawberry plant named 'BG-12.3266' is primarily adapted to the growing conditions of the central coast of California, and is primarily characterized by its orange red to red fruit color, medium fruit size, and cordate fruit shape, with very strong gloss; good fruit flavor, very firm fruit flesh, with seeds held even with the surface; very smooth fruit surface, even color, with only a slight difference between primary and secondary fruit; medium plant size, upright in habit, with medium density; medium yellow green foliage color, and medium foliage size; and fruit trusses typically held beneath the plant, with weak pubescence.

5 Drawing Sheets

2

BRIEF SUMMARY OF THE INVENTION

'BG-12.3266' is primarily adapted to the climate and growing conditions of the central coast of California. The 5 nearby Pacific Ocean provides the humidity and moderate temperatures needed to produce a strong, vigorous plant and maintain fruit quality during the winter and spring production months.

The following traits have been repeatedly observed and 10 are determined to be unique characteristics of 'BG-12.3266', which in combination distinguish this strawberry plant as a new and distinct variety:

1. Fruit ranges from orange red to red in color, medium in size, and cordate in shape, with very strong gloss;
2. Fruit has good flavor, very firm flesh, with seeds held even with the surface;
3. Fruit surface is very smooth, even in color, with only a slight difference between primary and secondary fruit;
4. Plant is medium in size, upright in habit, with medium density;
5. Foliage is medium yellow green in color, and medium in size; and
6. Fruit trusses are typically held beneath the plant, with weak pubescence.

The strawberry variety that is believed to be most closely related to the new variety 'BG-12.3266' is 'Inspire' (U.S. Plant Pat. No. 29,794). In side-by-side comparisons to the similar strawberry variety 'Inspire', 'BG-12.3266' differs by the following combination of characteristics as described in Table 1.

TABLE 1

Characteristic	'BG-12.3266'	'Inspire' (U.S. Plant Pat. No. 29,794)
Fruit: color	Ranges from orange red to red	Orange red
Fruit: season average size (gm)	28.5	26.6
Fruit: market yield season (gm/plt)	1,079	866
Fruit: flavor	Good (2.4 out of 5)	Excellent (3.7 out of 5)
Terminal leaflet: shape of base	Obtuse	Acute
Foliage: shape in cross section	Strongly to slightly concave	Flat to slightly convex
Petiole: size (cm)	13.4	10.2
Petiole: pubescence	Heavy	Moderate
Fruiting truss: position relative to foliage	Beneath	Above

For identification, a series of molecular markers have been determined for this new variety.

'BG-12.3266' differs from its parents, 'BG-3.324' and 'Florida Radiance' by the following combination of characteristics as described in Tables 2 and 3.

TABLE 2

Characteristic	'BG-12.3266'	'BG3.324' (U.S. Plant Pat. No. 23,256)
Fruit: season average size	Medium	Large
Time of flowering: harvest maturity	Medium	Early
Fruit: firmness of flesh	Very firm	Firm
Fruiting truss: position relative to foliage	Beneath	Ranges from level with to above

TABLE 3

Characteristic	'BG-12.3266'	'Florida Radiance' (U.S. Plant Pat. No. 20,363)
Fruit: season average size	Medium	Small
Fruit: color	Ranges from orange red to red	Red
Fruit: shape	Cordate	Long conical
Plant: size	Medium	Ranges from medium to small

BRIEF DESCRIPTION OF THE PHOTOGRAPHS

The accompanying color photographs illustrate the overall appearance of typical specimens of the new strawberry variety 'BG-12.3266' at various stages of development, as true as it is reasonably possible with color reproductions of this type. Color in the photographs may differ slightly from the color value cited in the botanical descriptions which accurately describe the color of 'BG-12.3266'. The depicted plant and plant parts of the new strawberry variety 'BG-

12.3266' are approximately six months old. The photographs were taken in Ventura County, Calif.

FIG. 1 shows fruiting field characteristics of 'BG-12.3266', taken in the month of April 2020;

5 FIG. 2 shows upper and lower surfaces of flower and flower parts of 'BG-12.3266', taken in the month of April 2020;

10 FIG. 3 shows typical fruiting truss and truss parts of 'BG-12.3266', taken in the month of April 2020;

15 FIG. 4 shows upper and lower surfaces of leaf and leaf parts of 'BG-12.3266', taken in the month of April 2020; and

FIG. 5 shows internal and external mature fruit characteristics of 'BG-12.3266', taken in the month of April 2020.

DETAILED BOTANICAL DESCRIPTION

The new variety 'BG-12.3266' has not been observed under all possible environmental conditions. The characteristics of the new variety 'BG-12.3266' may vary in detail, depending upon variations in environmental factors, including weather (temperature, humidity and light intensity), day length, soil type and location. In addition, the characteristics of any parental variety or comparison variety included in Tables 1, 2 and 3 of the present invention may vary in detail, depending upon variations in environmental factors, including weather (temperature, humidity and light intensity), day length, soil type and location.

20 The aforementioned photographs, together with the following description of the new variety 'BG-12.3266', unless otherwise noted, are based on observations taken during the 2020 growing season in Ventura County, Calif. These measurements and ratings were taken from plants of 'BG-12.3266' dug from a high-elevation nursery located in Siskiyou County, Calif. during early October 2019 and planted approximately four to five days later in Ventura County, Calif. The approximate age of the observed plants is five to six months. Yield observations including average weight and marketable yield, along with fruit quality characteristics including soluble solids, are averaged from five years of data collected from the 2016 through 2020 growing seasons. Flower measurements and characteristics are from secondary flowers unless otherwise noted. Fruit characteristics and measurements are from secondary fruit, unless otherwise noted.

30 35 40 45 Where noted, color terminology follows The Royal Horticultural Society Colour Chart, London (2007).

The following characteristics describe fruit, plant, stolon, foliage, fruiting truss, flower, reproductive organs and pest and disease characteristics of the new strawberry 'BG-12.3266'.

Fruit characteristics:

55 60 65 Color of mature fruit.—RHS 45B (ranges from orange red to red).

Color of internal flesh (excluding core).—RHS 34C (light red).

Color of core.—RHS 39A (medium red).

Average length (cm).—4.6.

Average width (cm).—3.8.

Size.—Ranges from medium to large.

Average length/width ratio.—1.23 (ranges from slightly longer than broad to much longer than broad).

Average calyx diameter (cm).—5.1.

Season average weight (gm).—28.5.

Achene color, shaded side.—RHS 153D (yellow green group).

<i>Achene color, sun-exposed side.</i> —RHS 184A (greyed purple group).		Foliage characteristics:
<i>Average achene weight (mg).</i> —0.60.		<i>Color of upper surface.</i> —RHS 137B (medium yellow green).
<i>Average achenes per berry.</i> —347.		<i>Color of underside.</i> —RHS 147C (yellow green group).
<i>Marketable yield season (gm/plant).</i> —1,079.	5	<i>Number of leaflets.</i> —3.
<i>Predominant shape.</i> —Cordate (cordiform).		<i>Leaf size.</i> —Medium.
<i>Difference in shape between primary and secondary fruit.</i> —Slight.		<i>Average length (cm).</i> —10.6.
<i>Band without achenes.</i> —Absent or very narrow.	10	<i>Average width (cm).</i> —13.7.
<i>Evenness of surface.</i> —Even or very slightly uneven.		<i>Average area foliage (cm²).</i> —145.4.
<i>Evenness of color.</i> —Even or very slightly uneven.		<i>Shape in cross section.</i> —Strongly to slightly concave.
<i>Glossiness.</i> —Strong.		<i>Interveinal blistering.</i> —Medium.
<i>Insertion of achenes.</i> —Level with surface.		<i>Leaf glossiness.</i> —Medium.
<i>Position of calyx attachment.</i> —Level.	15	<i>Leaf variegation.</i> —Absent.
<i>Attitude of sepals.</i> —Outward.		Petiole characteristics:
<i>Size of calyx in relation to fruit diameter.</i> —Slightly larger.		<i>Petiole color.</i> —RHS 146C (yellow green group).
<i>Adherence of calyx (when fully ripe).</i> —Strong.		<i>Average length (cm).</i> —13.4.
<i>Firmness of flesh.</i> —Very firm.	20	<i>Average diameter (mm).</i> —2.9.
<i>Distribution of red color of the flesh.</i> —Marginal and central.		<i>Petiolule color.</i> —RHS 146C (yellow green group).
<i>Hollow center expression.</i> —Weak.		<i>Petiolule average length (mm).</i> —3.6.
<i>Flavor.</i> —Good.		<i>Attitude of hairs.</i> —Strongly outward.
<i>Soluble solids (% Brix).</i> —8.6.		<i>Frequency of bract leaflets.</i> —None (0% occurrence).
<i>Flowering season (50% of plants with at least one flower).</i> —Medium (December in Ventura County, Calif.).		<i>Size of bract leaflets.</i> —N/A.
<i>Maturing season (50% of plants with mature fruit).</i> —	30	<i>Pubescence.</i> —Heavy.
Medium (January in Ventura County, Calif.).		
<i>Harvest period.</i> —January to May (in Ventura County, Calif.).		Stipule characteristics:
<i>Harvest maturity.</i> —Mid-season (in Ventura County, Calif.).		<i>Color.</i> —RHS 146B (yellow green group).
<i>Type of bearing.</i> —Not remontant.	35	<i>Anthocyanin coloration.</i> —RHS 62C (red purple group).
<i>Shipping quality.</i> —Very good.		<i>Anthocyanin intensity.</i> —Absent or very weak.
<i>Storage life at 1-3 degrees Celsius.</i> —7-10 days.		<i>Average length (mm).</i> —13.2.
<i>Market use.</i> —Fresh.		<i>Average width (mm).</i> —10.5.
Plant characteristics:	40	Fruiting truss characteristics:
<i>Average height (cm).</i> —16.8.		<i>Anthocyanin coloration.</i> —RHS 181C (greyed red group).
<i>Average spread (cm).</i> —32.4.		<i>Anthocyanin intensity.</i> —Weak.
<i>Size.</i> —Medium.		<i>Average length at maturity (cm).</i> —22.3.
<i>Habit.</i> —Upright.		<i>Position relative to foliage.</i> —Beneath.
<i>Density.</i> —Medium.	45	<i>Flower quantity (season average per plant).</i> —45 to 55 (medium).
<i>Vigor.</i> —Strong.		<i>Average number of flowers per truss.</i> —Medium.
<i>Hardiness zones.</i> —9-10.		<i>Primary pedicel color.</i> —RHS 146C.
Stolon characteristics:		<i>Primary pedicel length (cm).</i> —18.3.
<i>Color.</i> —RHS 146C (yellow green group).		<i>Pedicel attitude of hairs.</i> —Upward.
<i>Anthocyanin coloration.</i> —RHS 181B (greyed red group).	50	<i>Pubescence.</i> —Weak.
<i>Anthocyanin intensity.</i> —Medium.		<i>Attitude at first pick.</i> —Prostrate.
<i>Pubescence.</i> —Medium.		Flower characteristics:
<i>Attitude of hairs.</i> —Upward.		<i>Petal color (upper surface).</i> —RHS NN155C (white group).
<i>Average quantity in nursery (per square foot).</i> —6 to 7 (medium).	55	<i>Sepal color (upper surface).</i> —RHS 137B (green group).
<i>Average diameter at the first bract (mm).</i> —2.7 (thin).		<i>Corolla (flower) average diameter (mm).</i> —27.5 (medium).
<i>Length from mother plant to first daughter (cm).</i> —33.1.		<i>Calyx average diameter (mm).</i> —34.3.
Terminal leaflet characteristics:		<i>Petal average length (mm).</i> —10.4.
<i>Average length (cm).</i> —7.5.	60	<i>Petal average width (mm).</i> —9.7.
<i>Average width (cm).</i> —6.3.		<i>Petal average length/width ratio.</i> —1.07 (longer than broad).
<i>Average area terminal (cm²).</i> —46.8.		<i>Average petals per flower.</i> —6.0.
<i>Average length/width ratio.</i> —1.19 (longer than broad).		<i>Sepal average length (mm).</i> —14.3.
<i>Shape of base.</i> —Obtuse.		<i>Sepal average width (mm).</i> —4.5.
<i>Margins (shape of teeth).</i> —Rounded (crenate).	65	<i>Sepal average length/width ratio.</i> —3.21.
<i>Average serrations per leaf.</i> —22.7.		<i>Average sepals per flower.</i> —12.3.
		<i>Size of calyx relative to corolla.</i> —Larger.
		<i>Size of inner calyx relative to outer calyx.</i> —Ranges from smaller to same.

US PP33,450 P2

7

Relative position of petals (flowers with 5 or 6 petals).—Ranges from touching to overlapping.
Reproductive organs:
Receptacle/ovary color.—RHS 147C (yellow green group).
Anther/pollen color.—RHS 14A (yellow orange group).
Stamen.—Present.
Pollen amount.—Abundant.
Disease and pest reactions:
Powdery mildew (Sphaerotheca macularis).—Moderately resistant.

5

10

8

Angular leaf spot (Xanthomonas fragariae).—Moderately susceptible.
Botrytis fruit rot (Botrytis cinerea).—Moderately susceptible.
Fusarium wilt (Fusarium oxysporum).—Susceptible.
Anthracnose crown rot (Colletotrichum fragariae).—Susceptible.
Two-spotted spider mite (Tetranychus urticae).—Moderately susceptible.
We claim:

1. A new and distinct strawberry plant named 'BG-12.3266', as herein described and illustrated.
